UNITED STATES PATENT OFFICE

97,866

DESIGN FOR AN ENSEMBLE DRESS

Emil Schwartz, New York, N. Y.

Application November 2, 1935, Serial No. 59,328

Term of patent 3½ years

To all whom it may concern:

Be it known that I, Emil Schwartz, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

The rows of looped lines on the sleeves and neck portions of the jacket, and on the sleeves of the dress member of the ensemble, represent knotted cording forming open-work.

I claim:

The ornamental design for an ensemble dress, substantially as shown, and described.

EMIL SCHWARTZ.
